PRIMER

John P. Catlin, Fairfield, Conn., assignor to Remington Arms Company, Inc., Bridgeport, Conn., a corporation of Delaware

Application June 12, 1945, Serial No. 599,081

4 Claims. (Cl. 102—45)

1

The present invention relates to a primer, and has for its object to provide a primer which will be effectually leak proof in cooperation with a cartridge case formed of aluminum, or of other material having substantially the same characteristics of aluminum.

In the usual cartridge case of brass or steel primer leaks are by no means uncommon, but have been considered only a minor defect because they cause no serious trouble. In contrast, however, primer leaks are extremely serious in an aluminum case since the low melting point, high chemical reactivity, and high heat of oxidation of aluminum combine with what would otherwise be a trivial primer leak to give very serious erosion of the primer pocket and the base of the case, the powder gas from the fired cartridge causing an inconsequential primer leak to develop into a melting white-hot erosion of the case. Often the erosion is so serious that a considerable portion of the base material of the case is burned out in a very hot flame which seriously erodes the bolt face and endangers the gunner. In addition to the erosion characteristics of aluminum there also exists the mechanical condition resulting from the combination use of different metals, i. e. a primer cup of brass or similar material and a case of aluminum or similar material. The following are examples: elastic expansion of the primer cavity diameter of aluminum case faster than the expansion of a brass primer cup; plastic expansion of the primer cavity diameter under compressive stresses; lower yield strength of aluminum in comparison with other metals, such as brass and steel; and more rapid expansion under impact loading because of the mass-inertia effect, i. e. the more rapid acceleration of a given volume of less dense aluminum in comparison to such metals as brass or steel.

It is an object of the invention to provide a primer wherein a continuous annular region of contact between the primer cup and primer cavity walls will be maintained under a higher pressure than that of the powder gas itself, and to accomplish this within sufficiently wide limits so as to maintain an effective seal under any mechanical differential that may exist in the diverse materials of which the primer cup and case are constructed.

It is particularly proposed to provide a primer in which is assembled a conical washer engaged at its periphery with the wall of the primer cup, and adapted through the force of the primer explosion to flatten and thrust outwardly at its

2

periphery to produce, by plastic deformation of the primer cup wall and indentation of the primer pocket, a continuous annular region of contact which firmly and positively seals the primer and powder explosion gases within the case.

It has been found that external staking of the case to retain the primer cup in the primer pocket has a tendency to give the primer pocket a barrel shape which predisposes toward leaks, and is an object of the invention to provide a primer which is internally staked at the base of the primer pocket through the process of assembling the primer cup in the pocket, with the result that the staked area not only effectually retains the cup against outward thrust under the force of the explosion gases but constitutes a supplementary gas sealing band.

With the above and other objects in view, an embodiment of the invention is shown in the accompanying drawings, and this embodiment will be hereinafter more fully described with reference thereto, and the invention will be finally pointed out in the claims.

In the drawings:

25 Fig. 1 is a vertical sectional view of the primer, according to the invention, showing the primer mixture, anvil, and conical washer assembled therein prior to turning of the lip of the cup.

Fig. 2 is a similar view, showing the lip of the 30 cup turned preparatory to assembly in the primer pocket of the cartridge case.

Fig. 3 is a vertical sectional view, showing the primer assembled with the cartridge case.

Fig. 4 is a similar view, showing the relation 35 of the parts of the primer following firing of the primer mixture.

Similar reference characters indicate corresponding parts throughout the several figures of the drawing.

40 Referring to the drawings, the primer, according to the illustrated exemplary embodiment of the invention, is adapted to be assembled in the primer pocket 10 of the cartridge case 11, the latter being formed of aluminum or material of

45 similar characteristics. The primer comprises a primer cup 12, preferably formed of brass or material of similar characteristics, and includes an end wall and a side wall, the end wall in its initial state before assembly of the other parts of

50 the primer being preferably domed and the side wall being cylindrical between the end wall and the open end of the cup, as shown in Fig. 1. Within the primer cup there is inserted the primer mixture 13, an anvil 14, and a conical washer 15, the anvil being of generally hollow conical form,

and provided with oppositely disposed flash openings 16 in its periphery. The washer 15 is coned at a relatively low angle and snugly engages at its periphery within the wall of the cup 12. The parts of the primer are retained in assembled relation by turning the lower end of the side wall of the cup into downwardly and inwardly inclined conical form below the conical washer 15, as at 17, the domed end wall of the cup being flattened to cause the central area of the primer mixture to be constricted, while the marginal area is spread downwardly about the upper end of the anvil. The anvil is preferably formed of brass, while the conical washer 15 is preferably formed of copper plated suitably heat treated steel, so that it is relatively hard and strong and has the capability upon being flattened of exerting outward thrust at its periphery upon the wall of the cup to accomplish the plastic deformation of the latter.

The primer is assembled in the primer pocket of the case, as shown in Fig. 3, the downward assembling force exerted thereon causing the conical lip 17 to flatten against the base of the pocket, so that its inner periphery 18 is in substantial register with the flash hole 19 in the web 20 of the case. At the same time, the area at the base of the cylindrical wall of the cup, in line with the outward thrust upon the lip as the latter is flattened, is forced outwardly into the cylindrical wall of the primer pocket, forming a continuous annular interlocking seal 21, produced by the outward plastic deformation of the metal at the lower corner of the primer cup pressing into and slightly indenting the wall of the pocket adjacent its base. Thus an internal stake is produced which effectually prevents the cup from being thrust outwardly from the force of the primer and powder explosion gases. This staking also provides a continuous gas sealing band which supplements the gas sealing action of the conical washer, as will presently more fully appear. It will be observed that the internal stake 21 is below the area of the cup wall in lateral line with the periphery of the conical washer, and in which area the sealing action of the washer takes place. In assembling the primer into the primer pocket, the end wall of the primer cup is preferably dimpled at its center, as at 22, in opposed relation to the point of the anvil.

Upon firing, the explosive force of the primer mixture, as it passes through the flash passages 16 to the flash hole 19 flattens the conical washer 15, as shown in Fig. 4, causing its periphery to thrust outwardly against the wall of the primer cup, which is thereby plastically deformed and pressed into the wall of the primer pocket, causing the latter to be slightly indented, as at 23. This produces a firm and positive seal along a continuous annular area of contact between the primer cup and primer pocket. This action, in cooperation with the retention of the primer cup against outward thrust by the internal stake 21, and the supplemental gas seal provided by this internal stake, provides an effectual seal against the escape between the primer cup and the primer pocket of the primer and powder explosion gases.

The form of the invention illustrated in the drawings and described herein is typical and illustrative only, and it is evident that the invention is capable of embodiments in other forms, all falling within the scope of the appended claims, which are to be broadly construed.

What is claimed is:

1. In a primer for cartridges, a primer cup having an end wall and a circumferential side wall and adapted to have a primer charge confined within it, an anvil member engaged within said cup, and a deformable expansion member engaged beneath said anvil having its periphery engaged internally with said side wall and adapted through the explosive force of said primer charge to be deformed whereby its periphery is expanded to exert outward pressure on said side wall.
- 5 2. A primer for cartridges comprising a primer cup having an end wall and a circumferential side wall, a primer charge confined within said cup in contact with said end wall, an anvil member engaged within said cup in opposed relation to said end wall, and an apertured conical washer member engaged beneath said anvil having its periphery engaged internally with said side wall and adapted through the explosive force of said primer charge to be flattened whereby its periphery is expanded to exert outward pressure on said side wall, said circumferential side wall being flanged inwardly beneath said washer.
- 10 3. A primer for cartridges comprising a primer cup having an end wall and a circumferential side wall, a primer charge confined within said cup in contact with said end wall, an anvil member engaged within said cup in opposed relation to said end wall, and apertured conical washer member engaged beneath said anvil having its periphery engaged internally with said side wall and adapted through the explosive force of said primer charge to be flattened whereby its periphery is expanded to exert outward pressure on said side wall, said circumferential side wall being flanged inwardly beneath said washer in downwardly and inwardly inclined relation and adapted upon insertion of the primer in the primer cavity of a cartridge to flatten into engagement with the base of said cavity and through said flattening to be stressed outwardly into tight engagement with the wall of said cavity.
- 15 4. In combination, a cartridge case having a primer cavity in its head, and a primer engaged in said cavity comprising a primer cup having an end wall and a circumferential side wall, a primer charge confined within said cup, and a deformable expansion member having its periphery engaged internally with said side wall, and adapted through the explosive force of said primer charge to be deformed whereby its periphery is expanded to exert outward pressure on said side wall of said cup against the side wall of said cavity, said side wall of said cup being flanged inwardly beneath said expansion member and being engaged with the base of said primer cavity, the outer periphery of said flange being outwardly projected into interlocking staked engagement with the side wall of said primer cavity.
